CLAIM

The ornamental design for a media distribution hub enclosure as shown and described.

DESCRIPTION

FIG. 1 is a front top right perspective view of a media distribution hub enclosure thereof.

FIG. 2 is a front view of the media distribution hub enclosure thereof.

FIG. 3 is a back view of the media distribution hub enclosure thereof.

FIG. 4 is a left side view of the media distribution hub enclosure thereof.

FIG. 5 is a right side view of the media distribution hub enclosure thereof.

FIG. 6 is a top view of the media distribution hub enclosure thereof; and,

FIG. 7 is a bottom view of the media distribution hub enclosure thereof.

The broken lines shown in FIGS. 1-7 represent portions of the media distribution hub enclosure that form no part of the claim.

1 Claim, 7 Drawing Sheets
